DESCRIPTION

U.S. PATENT DOCUMENTS

FIG. 1 is a top, front and right side perspective view of a
ready to assemble modular storage unit showing my new
design;

211,093 * 1/1879 Henry 217/14
D. 232,340 * 8/1974 Lax D7/708
D. 233,872 * 12/1974 Jester D6/484
D. 255,853 * 7/1980 Tome D6/436
D. 260,837 * 9/1981 Tome D6/436
D. 273,066 * 3/1984 Kneale, III D6/462
925,799 * 6/1909 Boyd 217/36
1,983,436 * 12/1934 Brunaa ..... 217/12 R
2,960,238 * 11/1960 Park 211/134
3,612,289 * 10/1971 Zink 108/180
4,321,873 * 3/1982 Nealis 108/91

FIG. 2 is a bottom and rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged fragmentary view of the lower left and
front portions of FIG. 1;

FIG. 10 is an enlarged fragmentary view of the lower left
portions of FIG. 2; and,

FIG. 11 is a top, front and right side perspective view of a
second embodiment of my new design.
